RAZOR BLADE SHARPENER

Herbert L. Kriechbaum, Burlington, Iowa

Application November 3, 1939, Serial No. 302,766

5 Claims. (Cl. 51—205)

This invention relates to a blade sharpener and more particularly to a sharpener by use of which a blade for a safety razor may be burnished and a keen cutting edge formed.

One object of the invention is to provide a blade sharpener which is new in principle and of simplified construction and consists of a pair of rollers formed of hardened steel and rotatably mounted at free ends of the arms of a frame formed from a strip of resilient metal.

Another object of the invention is to provide a sharpener having a frame adapted to be easily held in a person's hand between the thumb and first finger and pressure applied to arms of the frame to force the arms and rollers carried thereby toward each other into position to cause the rollers to have close contacting engagement with the edge of a razor blade disposed between the rollers.

Another object of the invention is to provide a blade sharpener wherein either heavy or light pressure may be applied to the cutting edge of a razor blade and a good burnishing action take place when the blade and the sharpener are moved relative to each other longitudinally of the blade engaging rollers.

Another object of the invention is to so form the frame that its arms will be provided with tongues at its front end between which the rollers are rotatably mounted, one arm having a thumb-receiving depression or pocket causing the arms to be firmly held in proper relation to each other and prevented from slipping from between a thumb and finger during use of the sharpener.

Another object of the invention is to provide a sharpener which may be used for sharpening a razor of the open blade type or for sharpening safety razor blades which may be either thick or thin.

Another object of the invention is to provide a blade sharpener which is simple in construction, very efficient and dependable and fool-proof in operation, cheap to manufacture, and of such dimensions that it may be carried in a pocket when not in use.

With these and numerous other objects in view, my invention consists in the novel features of construction, combination and arrangement of parts as will be hereinafter referred to and more particularly pointed out in the specification and claims.

The invention is illustrated in the accompanying drawing wherein:

Figure 1 is a perspective view of the improved sharpener;

Figure 2 is a sectional view taken longitudinally through the sharpener;

Figure 3 is a view showing the sharpener in use for sharpening the cutting edge of an open blade razor;

Figure 4 is a similar view showing the sharpener in use for sharpening a safety razor blade;

Figure 5 is a sectional view taken longitudinally through the sharpener with its rollers in engagement with a blade to be sharpened; and

Figure 6 is a view similar to Figure 4 and showing the sharpener held stationary and the blade reciprocated instead of holding the blade stationary and reciprocating the holder as shown in Figure 4.

This improved blade sharpener has a frame 1 formed from a strip of resilient metal such as spring steel which is folded midway its length to form companion arms 2 and 3 integrally united at their rear ends by a spring portion 4. At its ends the strip is formed with longitudinally extending tongues located at opposite sides of the strip and bent along diagonal lines at their inner ends to provide ears 5 and 6 between which rollers 7 of hardened steel are rotatably mounted by shafts or axles 8. The ears or bearing members extend longitudinally of the arms from their front ends and are of such length that the rollers will meet one above the other forwardly of the arms when the arms are forced toward each other from the position of Figure 2 to that of Figure 5. By so mounting the rollers the cutting edge of a razor blade 9 or the cutting edge of the blade 10 of a straight razor 11 may be disposed between outer portions of the rollers and the blade held stationary while the sharpener is reciprocated longitudinally of the blade to burnish the cutting edge portion of the blade and form a smooth and very keen cutting edge.

Instead of holding the blade stationary and reciprocating the sharpener, as shown in Figures 3 and 4, the sharpener may be held stationary and the blade reciprocated as shown in Figure 6. The rollers are forced toward each other by pressure applied to the two arms with the thumb and first finger of the hand holding the sharpener and in order that the sharpener may be easily held and prevented from slipping when pressure is applied to the arms, the arm 2 has been formed with a depressed cup-shaped portion or seat 12 to receive the thumb. When sharpening a thin blade light pressure will be applied and for a thick blade greater pressure will be applied. The first finger which extends transversely across the arm constitutes a backing member and the pressure is applied with the

thumb. Since the thumb is seated in the pocket 12 it cannot slip longitudinally or transversely of the arm 2 and the pressure will be properly centered and the rollers maintained in direct 5 opposed relation to each other as shown in Figure 5. When pressure upon the arms is released the resiliency of the metal strop from which the frame is formed causes the arms to spring apart and return to the normal position of Figure 2 10 which spaces the rollers from each other. The sharpener is quite small and can be easily held in a person's hand when it is in use. When the sharpener is not in use it may be placed upon a shelf in a medicine cabinet where it will occupy a small amount of space or it may be conveniently 15 carried in a vest pocket. While it has been stated that the device is for use as a sharpener for a razor blade it is obvious that it may be used for burnishing and sharpening the cutting edge 20 of a knife blade or any other blade having a cutting edge.

From the foregoing description of the construction of my improved device, the operation thereof and the method of applying the same to 25 use, will be readily understood. It will be seen that I have provided a simple, inexpensive and efficient means for carrying out the objects of the invention and while I have particularly described the elements best adapted to perform 30 the functions set forth, it is obvious that various changes in form, proportion and in the minor details of construction may be resorted to, without departing from the spirit or sacrificing any of the principles of the invention.

35 Having thus described the invention, what is claimed is:

1. A blade sharpener comprising a frame formed from a strip of resilient material folded midway its length to provide arms having their 40 rear ends united by a curved spring portion, tongues at ends of said strip extending longitudinally thereof in spaced relation to each other transversely of the strip and bent along diagonal lines at their inner ends to provide bearing ears projecting forwardly from the arms, and rollers of hardened metal rotatably mounted 45 between companion ears and extending transversely of the arms in spaced relation to front ends thereof, one arm being formed adjacent its

front end with a depressed portion constituting a thumb receiving seat.

2. A blade sharpener comprising a frame having arms extending forwardly in diverging relation to each other and yieldably held against movement toward each other, ears extending forwardly from front ends of said arms at opposite sides thereof, the ears being disposed diagonally of the arms and the ears of each arm extending forwardly therefrom in converging relation to 10 ears of the other arm, and rollers of hardened metal rotatably mounted between companion sets of ears and extending transversely of the arms in forwardly spaced relation to their front ends, one arm being formed adjacent its front end with 15 a depressed portion forming a thumb-receiving seat.

3. A blade sharpener comprising a frame having resilient arms extending in forwardly diverging relation to each other, ears projecting forwardly from front ends of said arms and spaced from each other transversely of the arms, and rollers of hardened metal rotatably mounted between companion ears and extending transversely of the arms in spaced relation to front ends thereof, one arm being formed adjacent its front end with 20 a depressed portion forming a thumb-receiving seat. 25

4. A blade sharpener comprising a frame having arms extending forwardly in diverging relation to each other and yieldably held against movement toward each other, ears extending forwardly from front ends of said arms and spaced from each other transversely of the arms, and rollers of hardened metal rotatably mounted 30 between companion ears and spaced forwardly from front ends of the arms in position to make contact with each other when the arms are pressed toward each other.

5. A blade sharpener comprising a frame having arms diverging forwardly from each other and yieldably held against movement toward each other, bearings at front ends of said arms, and rollers of hardened metal rotatably mounted between companion bearings and extending transversely of front ends of the arms in position to 40 make contact with each other when the arms are pressed toward each other. 45
